UNITED STATES PATENT OFFICE.

EDWARD P. SHELDON, OF NEW YORK, N. Y., ASSIGNOR TO R. HOE AND CO., OF NEW YORK, N. Y., A CORPORATION OF NEW YORK.

ASSEMBLING MECHANISM.

1,081,519.

Specification of Letters Patent. Patented Dec. 16, 1913.

Application filed January 25, 1910. Serial No. 539,961.

To all whom it may concern:

Be it known that I, EDWARD P. SHELDON, a citizen of the United States, residing at New York, county of Kings, and State of New York, have invented certain new and useful Improvements in Assembling Mechanism, fully described and represented in the following specification and the accompanying drawings, forming a part of the same.

This invention relates to certain improvements in means for assembling printed products.

In producing a certain class of printed products, such, for instance, as weekly papers or magazines consisting of a considerable number of plies, it is usual to sever the plies by a cutter which has a slightly serrated edge, as such a cutter operates more satisfactorily at high speed than a cutter which does not have its edge so formed. The serrated cutters, however, produce a product having a more or less rough edge, so that the product has a somewhat unfinished appearance. In many cases, this unfinished appearance is objectionable, and it is, therefore, customary to trim the product. The objectionable appearance of such a product can, however, be overcome by uniting with it an outer or cover sheet or sheets having what is ordinarily termed a clean cut edge, this outer or cover product being composed of a sheet or sheets which are slightly longer than the sheets of the inner product, so that the cover product overlaps and hides the rough edges of the inner product, thus making it unnecessary to trim the complete product.

The present invention has for one of its objects to produce a mechanism which will assemble with an inner product an outer product which is slightly longer than the inner product, the products being assembled so that their transverse fold lines will be in register.

A further object of the invention is to produce a mechanism which will assemble two products of different lengths with their transverse centers, on which the product is folded, in register, said mechanism including suitable devices for securing the products together.

A further object of the invention is to produce certain improved details of construction which may be advantageously employed in carrying the invention into effect.

With these and other objects not specifically referred to in view, the invention consists in certain constructions, and in certain parts, improvements and combinations as will be hereinafter fully described and then specifically pointed out.

Referring to the drawings—Figure 1 illustrates, in diagrammatic side elevation, an assembling mechanism embodying the invention, Fig. 2 is an end elevation, partly in section, of an assembling cylinder which may be employed, and parts immediately connected therewith, the view being on an enlarged scale, as compared with Fig. 1. Fig. 3 is a plan view of the assembling cylinder illustrated in Fig. 2. Figs. 4 to 10 are detail sectional views illustrating the operation of certain grippers which may be employed on the assembling cylinder.

In the particular machine which has been selected to illustrate the invention a plurality of webs W, W are shown as passing between a set of bending rolls 1 and nipping rolls 2 which operate to bring the webs together. Sheets cut from these webs will form the interior plies of the product to be finally produced by the machine, these sheets being assembled with the outer sheet or sheets by an assembling mechanism which may be varied widely in construction. In the particular machine shown, the assembling mechanism includes a cylinder 3 which may, as shown, form one of a pair of cutting cylinders for severing the webs into sheets, the companion cylinder being illustrated at 4. In the particular construction illustrated, the assembling cylinder is provided with three cutting blocks or woods 5, and the cylinder 4 is provided with the usual knife 6 cooperating therewith.

The form of cutting mechanism which has just been described in which the assembling cylinder carries one member of the cutting device, is an excellent one for carrying the invention into effect, but it is to be understood that the invention is not restricted to cutting mechanism in which the assembling cylinder when employed carries one of the cutting members. It is of course apparent that the sheets formed by the cutting mechanism referred to will be of equal and predetermined length.

The assembling cylinder, when this form of assembling mechanism is employed,

should be provided with devices for taking the sheets formed by the cutting devices. While these devices may be varied, in the particular construction illustrated, the sheets are taken by pairs of side grippers 7 pivoted in the ends of the cylinder, the projecting tails 8 of the grippers being provided with cam rolls 9 and arranged to contact as the cylinder rotates with operating cams 10 secured to the frame of the machine, the construction being a usual one. The side grippers referred to take the leading ends of the webs and carry the webs forward, the cutting devices operating in the usual manner to sever the sheets from the webs.

Machines embodying the invention will include means for delivering to the assembling cylinder an outer sheet or sheets which will be slightly longer than the interior sheets, and one of these sheets may, if desired, form a cover. The difference in length will be slight, usually about a quarter of an inch, so that the edges of the exterior sheet or sheets will extend about one-sixteenth of an inch on each side beyond the edges of the interior sheets, thus hiding any roughness of cut on the interior sheets and giving the entire product, after the outer sheet or sheets have been applied, the appearance of a product which has been trimmed. The means for presenting to the assembling mechanism this outer sheet or sheets may be considerably varied. In the machine shown, the outer sheet or sheets, indicated at S, are assumed to be alternately forwarded from two sources, the sheets from one source being initially forwarded by a set of feeding rolls 11, through a tape pathway 12 of ordinary form, to a sheet rest 13. Sheets from the other source are forwarded by a pair of feeding rolls 14, through an ordinary tape pathway 15, to a sheet rest 16. The sheet rests 13 and 16 have timing stops 17 co-operating therewith, these timing stops being alternately operated through mechanism of the usual type indicated in dotted lines in Fig. 1 and not necessary to specifically describe, as it is well understood in the art. The sheets from the rest 13 are forwarded by a tape pathway 18 to a sheet support 19, and the sheets from the sheet rest 16 are forwarded by an ordinary tape pathway 20 to the sheet support 19, both sets of sheets passing between forwarding rollers 21. The inner edge of the support 19 is so located with respect to the assembling cylinder 3 as to deliver the sheets passing thereover to the sheets on the cylinder which have been cut from the webs as before referred to. The forwarding devices for the sheet which pass over the support 19 are, however, so timed as to cause these sheets to be presented to the web sheets on the cylinder 3 with their edges slightly in advance

of the edges of the web sheets. It will be understood that the sheets passing over the support 19 are, as has been indicated, slightly longer than the web sheets, and although their leading edges when they reach the cylinder 3 are slightly in advance of the web sheets on the cylinder, the transverse centers of the two sets of sheets will be in register.

The assembling mechanism will be provided with means for taking the exterior sheets. While the construction of these taking devices may be varied, in the construction illustrated, they comprise a set of edge grippers, these grippers including gripper fingers 22 which operate upon the edges of the exterior sheets. While these edge grippers, when employed, may be variously mounted and operated, in the best construction they will be arranged so as to move from an inoperative position below and at one side of the cutting member to a position over it. In the particular construction illustrated, each set of fingers is carried on a shaft 23 mounted in the cylinder the ends of the cylinder being slotted, as at 24, to permit the shafts to move. Each of the shafts 23 is carried in arms 25 pivoted on a shaft 26 also mounted in the cylinder, these shafts 26 having operating arms 27 extending therefrom provided with rolls 28. The shafts 23 have operating arms 29 extending therefrom, these arms being provided with rolls 30. The rolls 28 are arranged to contact with cams 31 carried on the frame in which the cylinder is mounted, and the rolls 30 are arranged to contact with cams 32 also carried on the frame. The cams 31 and 32, through the connections indicated, give the grippers a compound movement which causes them to be carried from an inoperative position against a rest 33 below and at one side of the cutting member 5 to an operative position over said member.

The sheet S, in the particular machine shown, are advanced by a roll 34 which co-operates with the roll 3 before referred to, this roll having a cut out portion 35 to permit the operation of the edge grippers before referred to. The operation of these grippers will be well understood from the detail views 4 to 10 inclusive. In the first of these views, the edge grippers 7 have taken the leading ends of the webs and are carrying them forward and the sheets S are shown in position to enter between the cylinders 3 and 34. In Fig. 5, the cylinder has rotated somewhat and the fingers 22 which are shown in inoperative position in Fig. 4 have begun their movement away from the rest 33 and are pushing the tails of the previously taken sheets which tails are overlapped slightly by the leading edge of the incoming sheet S, back into the recess 35 in the cylinder 34. Figs. 6 and 7 show suc-

sive positions of the parts. In Fig. 7, the grippers 22 are shown as having nearly completed their movement toward the cylinder 34, the leading edge of the sheet S having been bent back and resting against the edges of the tails of the preceding sheets. In Fig. 8, the grippers 22 are shown as having entirely completed their movement toward the cylinder 34, the leading edge of the sheet S has been cleared from the tails of the preceding sheet, and have snapped back onto the cylinder 3, and the grippers 22 are ready to begin their closing movement, the position of the parts when the grippers have completed their movement and taken the edge of the sheet S being shown in Fig. 10. When the grippers 22 have closed upon the leading edge of the sheet S, the carrier 3 moves onward, advancing the sheets which have been taken by the two sets of grippers.

As has been stated, the leading edge of the sheets are so positioned and the sheets S are so controlled in their movement that when superposed upon the web sheets the transverse center lines of the two sets of sheets will be in register. When the sheets have been thus assembled they should be secured together. The securing may be effected in various ways, as, for instance, simply by folding the sheets, but in machines embodying the invention in its best form, means will be provided for positively uniting the sheets on their transverse center lines. When the securing means includes means for uniting the sheets, these means may be of various descriptions. As shown, the cylinder 34 is provided with a staple forming and inserting plunger 36, this plunger coöperating with a staple former 37 and a clenching member 38 on the cylinder 3. The form of stapling mechanism indicated in the drawings is well understood in the art and a specific description of it is unnecessary.

When the securing means includes a folding mechanism any suitable type of folder may be employed. In the particular machine illustrated, the cylinder 3 is provided with three tucking blades, indicated at 39, these blades operating to insert the sheets at their fold lines between nipping jaws 40 of a usual type mounted on a cylinder 41, this cylinder operating, as usual in such constructions, to deliver the folded product to a conveyer 42.

Changes and variations may be made in the construction by which the invention is carried into effect. The invention is not, therefore, to be confined to the particular construction herein shown and described.

60 What is claimed is:

1. The combination with means for forming a product of predetermined length, of means for assembling with said product a product differing slightly in length and derived from a different source, the products

being assembled with their transverse centers in register, and means for securing the products together.

2. The combination with means for forming a product consisting of a plurality of sheets of predetermined length, of means for forwarding and assembling therewith a slightly longer outer sheet derived from a different source, the sheets being assembled with their transverse centers in register, and means for securing the products together. 70

3. The combination with an assembling cylinder, of means for presenting thereto a product of a predetermined length, taking devices on the cylinder for said product, 80 means for presenting to the cylinder a second longer product derived from a different source with its transverse center in register with the transverse center of said first product, taking devices on the cylinder 85 for the second product, and means for securing the products together.

4. The combination with an assembling cylinder, of means for presenting thereto a product of a predetermined length, grippers on the cylinder for taking the product, means for presenting to said cylinder a second longer product derived from a different source with its transverse center in register with the transverse center of the first product, grippers on the cylinder for taking said second product, and means for securing the products together. 95

5. The combination with an assembling cylinder, of means for presenting a product of predetermined length thereto, side grippers on the cylinder for taking said product, means for presenting to said cylinder a second longer product derived from a different source with its transverse center in register with the transverse center of the first product, edge grippers on the cylinder for taking said second product, and means for securing the products together. 100

6. The combination with a pair of cutting cylinders one of which is an assembling cylinder, of means for presenting a plurality of webs thereto, means on the assembling cylinder for taking the cut product, means for assembling with the product on the assembling cylinder a second slightly longer product derived from a different source, said products being assembled with their transverse centers in register, means for taking said second product, and means for folding off said assembled product. 110

7. The combination with a pair of cutting cylinders one of which is an assembling cylinder, of means for presenting a plurality of webs thereto, means on the assembling cylinder for taking the cut product, means for assembling with the product on the assembling cylinder a second slightly longer product derived from a different source, said products being assembled with their trans- 125

- verse centers in register, means for taking said second product and means for folding off said assembled product, said means including a tucking blade carried by the assembling cylinder. 65
8. The combination with means for forwarding a product consisting of a plurality of sheets of predetermined length, means for forwarding and assembling with said product a slightly longer exterior product derived from a different source the products being assembled with their transverse centers in register, and stapling devices for securing the products together. 70
15. 9. The combination with means for forwarding a product consisting of a plurality of sheets of predetermined length, of means for forwarding and assembling therewith a slightly longer outer product derived from a different source the products being assembled with their transverse centers in register, and means for folding the assembled product. 75
10. The combination with means for forwarding a product consisting of a plurality of sheets of predetermined length, of means for forwarding and assembling therewith a slightly longer outer product derived from a different source the products being assembled with their transverse centers in register, and means for folding and stapling the assembled product. 80
11. The combination with an assembling cylinder, of means for presenting thereto a product consisting of inner plies and an outer ply of different length and derived from a different source, said plies having their transverse centers in register, taking devices, and staple inserting means operating to secure the plies together while on the assembling cylinder. 85
12. The combination with an assembling cylinder, of means for presenting thereto a product consisting of inner plies and an outer ply of different length and derived from a different source, said plies having their transverse centers in register, taking devices, staple inserting means operating to secure the plies together while on the assembling cylinder, and means for folding off the assembled and stapled product. 90
13. The combination with an assembling cylinder, of grippers carried thereby, cutting devices, means for presenting to the product held by the grippers a second slightly longer product derived from a different source, edge grippers for taking said product, and stapling devices. 95
14. The combination with an assembling cylinder, of grippers carried thereby, cutting devices, means for presenting to the product held by the grippers a second slightly longer product derived from a different source, edge grippers for taking said product, and folding devices. 100
15. The combination with an assembling cylinder, of grippers carried thereby, cutting devices, means for presenting to the product held by the grippers a second slightly longer product derived from a different source, edge grippers for taking said product, folding devices, and stapling devices. 105
16. The combination with a pair of cutting cylinders one of which is an assembling cylinder, of edge grippers thereon, means for presenting to the product on the assembling cylinder a second slightly longer product derived from a different source, a set of edge grippers for this second product, means for moving the grippers from an inoperative position below and at one side of the cutting member to an operative position over said member, and securing means. 110
17. The combination with an assembling cylinder carrying a cutter block, of a co-operating cutting cylinder, a pair of edge grippers, means for causing said grippers to take a product consisting of a plurality of sheets, means for presenting to the cylinder a second slightly longer product derived from a different source, with its transverse center in register with the transverse center of the first product, a pair of edge grippers for taking the longer product, and means for moving the grippers from an inoperative position below and at one side of the cutter block to an operative position over the cutter block, and means for securing the assembled products. 115
18. The combination with an assembling cylinder carrying a cutter block, of a co-operating cutting cylinder, a pair of edge grippers, means for causing said grippers to take a product consisting of a plurality of sheets, means for presenting to the cylinder a second slightly longer product derived from a different source with its transverse center in register with the transverse center of the first product, a pair of edge grippers for taking the longer product, means for moving the grippers from an inoperative position below and at one side of the cutter block to an operative position over the cutter block, and means for securing the assembled product, said means including stapling and folding devices. 120
- In testimony whereof, I have hereunto set my hand, in the presence of two subscribing witnesses.
